ADHESIVE TAPE PROPELLING MECHANISM

Seth B. Lindsey, Anoka, Minn., assignor to Minnesota Mining & Manufacturing Company, St. Paul, Minn., a corporation of Delaware

Application February 4, 1950, Serial No. 142,407

8 Claims. (Cl. 271—2.3)

1

This invention relates to mechanisms for propelling adhesive tape, particularly normally tacky and pressure-sensitive adhesive tape, and particularly mechanisms for the withdrawing of such tape from a supply and the projecting of lengths thereof into a desired position.

An objective is to provide such a mechanism or movement suitable for incorporation into a variety of types of tape handling devices, including manually operated devices, but especially automatic power driven dispensers and combined dispensers and applicators.

The invention provides a movement, the principal elements of which comprise a means for the withdrawal of tape from a supply, a tape-forming and projecting wheel having a grooved periphery and aligned to permit peripheral contact with withdrawn tape that is led to it from the withdrawing means, and a tape-forming guide adjacent the wheel positioned to bear against the tape to direct the tape into contact with the periphery of the wheel and to depress the tape into the groove. The tape-withdrawing means may comprise at least one "pull-off" roller which operates by peripheral driving connection with the tape.

Such a mechanism can be employed as a tape propelling element in dispensers, sealers, packaging machines and numerous types of tape handling machines and devices, particularly where the projection of a free unsevered length of tape forwardly into an open space is required.

A pull-off roller and the wheel in such a mechanism may be rotated continuously, where a continuous supply of tape is needed, or intermittently to allow for the disposal of a projected length before further tape is advanced.

Ordinarily the roller and the wheel would be rotated simultaneously at the same peripheral speed.

If desired, however, the roller may first be turned to withdraw a length from the supply whereupon the wheel may then be turned to project it; or the roller may be slowly turned continuously and the wheel intermittently. In such cases, it is desirable to have the roller and the wheel spaced apart sufficiently to allow for the temporary loop that would form between them, preferably with a means for tensioning the loop.

An illustrative embodiment is described below and illustrated in the attached drawings in which:

Figure 1 is a diagram of a specific form of the movement;

2

Figure 2 is a plan view of a tape-forming and projecting wheel and tape-forming guide;

Figures 3 and 4 are perspective views of the right rear and of the left side, respectively, of a sealing machine;

Figures 5 and 6 are fragmentary views, on the indicated sections, of the dispensing and applying mechanism of the machine; and

Figure 7 shows a paper folder or "mailing piece" that has been sealed by the machine.

Referring to Figures 1 and 2, a pull-off roller 11 is rotatably mounted to withdraw normally tacky pressure-sensitive adhesive tape from a supply thereof upon rotation of the roller, the roller being in peripheral driving connection with the tape by reason of the tape's temporary adherence to the periphery of the roller.

A tape-forming and projecting wheel 12 having a V-shaped groove 13 in its periphery, is rotatably mounted in a position to have the grooved portion of its periphery contacted by the adhesive side of tape that is fed to it by the roller 11. The periphery of the wheel, including the groove, is knurled.

Adjacent the wheel is a tape-forming guide in the form of a slender finger 14 extending into the groove and held in that position by a guide-supporting bar 15.

In operation, tape is first threaded from the supply around the periphery of the pull-off roller 11 and thence downwardly between the guide 14 and the groove 13 of the tape-forming and projecting wheel 12 with the adhesive side contacting the groove.

Upon rotation of the roller 11, the tape is withdrawn from the supply and fed to the wheel 12. Rotation of the wheel 12 draws the fed tape toward itself. As the tape moves toward the wheel the finger guide 14 bears or presses against the back of the tape in a manner to direct the tape into adhesive contact with the grooved portion of the periphery of the wheel 12 and to depress the tape into the groove 13.

The depression of the tape into the groove gives the tape a shape in cross section generally similar to the cross sectional shape of the groove, thus rendering the tape longitudinally ridged. The ridge extends along the tape's length for a distance on either side of its point of tangency to the wheel. This stiffens the tape enough so that it continues to thrust straight on after leaving the point of tangency and to pull loose from its adhesive contact with the wheel instead of following the wheel around.

As a result, a stiffened projected length T' of

the tape T is thrust out away from the wheel 12 in readiness for severing and removal. The severing may be by drawing it against a fixed knife 16.

The knurling on the periphery of the forming and projecting wheel 12 reduces the area of contact between the periphery and the adhesive side of the tape and thus makes it easier for the stiffened tape to pull itself loose from the wheel in the manner above described.

Thus the knurled area need extend only as far across the periphery as the width of the tape requires, and such partial knurling, as well as knurling across the full width of a periphery, is contemplated when using the expression "knurled periphery" herein.

The periphery of the pull-off roller 11 may also be knurled, although it is not as desirable as in the case of the projecting wheel 12 since the pull on the tape exerted by the wheel 12 may often be enough to remove the tape from its adhesive contact with the roller 11 even though the periphery of the roller is smooth.

Obviously forms of knurling other than those shown in the drawings may be used.

If desired, a wheel may be rotatably mounted on the end of the finger 14. This is particularly desirable in embodiments where the back and not the tacky side of the tape contacts the periphery of the forming wheel 12. In such embodiments the knurling on the periphery of the forming wheel 12 may sometimes be dispensed with.

The groove 13 may be other than V-shaped in cross section, as long as the tape becomes formed upon being depressed therein so as to stiffen it sufficiently to enable it to free itself from the wheel and extend into a desired position.

Tape-withdrawing means other than the illustrated single pull-off roller 11 may be employed as long as it operates to provide withdrawn tape in a position to be led to the wheel 12.

In the illustrated sealing machine the tape supply is in the form of a roll R of the tape mounted on a rotatable drum 29 at the front, the "front" being the side of the machine where a stack 17 of folders is held in readiness to be run through the machine and sealed. The terms "right," "left," etc. herein are from the point of view of an operator facing the front of the machine.

The pull-off roller 11 is fixed on the right end of a shaft 21 that is journaled into the frame of the machine, and the tape-forming and projecting wheel 12 is fixed on a similar shaft 22. Gears 23 and 24 are fixed on the left ends of the shafts 21 and 22, respectively (Figure 4). These are rotated by a larger gear 25, the three gears 23, 24 and 25 being of a size to produce rotation of the roller 11 and the wheel 12 at the same peripheral speed. The peripheral speed of the roller 11 is preferably the same as the peripheral speed of the bottom of the groove 13 of the wheel 12. The gear 25 is intermittently rotated clockwise (Figure 4) through an idler crank 26 and a ratchet by a continuously oscillating power-driven crank 27.

The crank 27 is oscillated by a pitman 28 and crank gear 29 which latter is continuously rotated by a motor 32 acting through a belt 33, pulley 34, chain 35 and sprocket 36, the latter being connected with the gear 29 by a small gear not shown.

The cranks 26 and 27 both turn freely on the shaft that holds the gear 25. When impelled clockwise (Figure 4) the crank 26 turns the gear

25 clockwise by means of a ratchet (not shown). The continuously oscillating power-driven crank 27 turns the idler crank 26 clockwise during a clockwise stroke of the crank 27 by bearing or pushing against a stud 37 that is on the crank 26. At the end of such a stroke, however, the crank 26 is in a "six-o'clock position" and normally remains so. Thus, unless it is returned to the "cocked" position shown in Figure 4, the further oscillation of the crank 27 will not turn the crank 26, the gear 25 will be motionless, and no further length of tape will be dispensed. The manner of cocking the crank 26 will be herein-after described.

Means for propelling a work piece or object to be sealed, such as a flexible folder 40, through the machine, is provided in the form of a large vacuum pick-up feed drum 41 having a deep circumferential channel 42 in its periphery extending around the drum. The drum is positioned to permit the unsevered projected length T' of tape to extend into the channel 42.

A plurality of suction apertures 43 pierce the periphery on either side of the channel for a portion of the drum's circumference. A vacuum pump 45 continuously operated by the motor 32 through the belt 33 and pulley 34, is connected by well known means including a rotary valve, not shown, to create a suction within the drum which acts through the apertures 43 to hold the flexible mailing folder 40 against the periphery of the drum in the manner shown in Figure 5.

The drum is continuously rotated clockwise (Figure 5) by the gear 29 which is fixed to the left end of the drum shaft 46. The vacuum connection with the drum is shut off and on by the rotary valve automatically as the drum rotates. The suction is normally off in the drum. It is turned on when the apertures are opposite a folder that is to be picked up from the stack 17. It is turned off after the sealing of the folder has been completed.

When a folder is thus picked up, the apertures are covered by the folder and the vacuum is thus completed in the drum. Acting through suitable connections, including the hose 47, this completion of the vacuum operates to draw up a piston in a cylinder 48, and the piston, being connected to the idler crank 26, draws the latter in a counter clockwise direction and cocks it (positions it as shown in Figure 4) so that the next clockwise stroke of the crank 27 will operate the tape projecting mechanism in the manner hereinabove described.

If there are no folders left in the stack 17 waiting to be picked up by the drum so that the apertures 43 are not covered, the vacuum is not completed, the piston in the cylinder 48 is not drawn up and the crank 26 is not cocked.

Thus the vacuum within the drum 41 is turned on and off continuously as long as the drum continues to rotate, but the tape projecting mechanism stops and starts continuously only as long as folders continue to be fed to the drum. If no folder is presented to the drum, no further tape is fed, even though the motor continues to run and the drum to rotate.

Soon after the leading edge of the moving folder 40 contacts the adhesive side of the uncut length of tape T', it begins to pass between a pair of sealing rollers 50 and 51.

The upper sealing roller 50 is carried by a frame 52, which also carries the knife 16, and is impelled downwardly by the spring 53 which acts to impel the frame about a fulcrum 54.

The lower sealing roller 51 is carried by a curved arm 55 which is fixed to the shelf 56 and extends upwardly therefrom within the channel 42.

At about the time that the folder is nipped between the sealing rollers 50 and 51, the tape is severed by being drawn rearwardly against the fixed knife 16. The sealing rollers press the upper and lower ends of the cut piece of tape into adhesive contact with the upper and lower surfaces, respectively, of the folder.

The sealing of the folder in the manner shown in Figure 7 has then been completed.

Immediately thereafter the suction is automatically shut off from the drum and the sealed folder drops off from the drum onto the sloping shelf 56 and thence onto the stack 57.

Numerous alternatives and changes of form may be employed within the scope of the invention. Some of these have been described above in connection with Figures 1 and 2. Additionally, for example, only one suction aperture 43 in the drum on each side of the channel may be employed instead of a plurality on each side, if desired.

I claim:

1. A normally tacky pressure-sensitive adhesive tape withdrawing and projecting mechanism comprising a pull-off roller for the withdrawal of tape from a supply by peripheral driving connection with the tape, a tape-forming and projecting wheel having a knurled grooved periphery and aligned to permit peripheral contact with the adhesive side of tape that is fed from the pull-off roller, a tape-forming finger adjacent the wheel positioned to bear against the back of the tape to direct the tape into adhesive contact with the periphery of the wheel and to depress the tape into the groove, means for rotating the roller and means for rotating the wheel.

2. The mechanism of claim 1 in which the periphery of the pull-off roller is knurled.

3. The mechanism of claim 1 in which the groove in the periphery of the wheel is V-shaped in cross section.

45

4. The mechanism of claim 3 in which the periphery of the pull-off roller is knurled.

5. A normally tacky pressure-sensitive adhesive tape withdrawing and projecting mechanism comprising a pull-off roller for the withdrawal of tape from a supply by peripheral driving connection with the tape, a tape-forming and projecting wheel having a knurled grooved periphery and aligned to permit peripheral contact with the adhesive side of tape that is fed from the pull-off roller, a tape-forming finger extending into the groove to bear against the back of the tape to direct the tape into adhesive contact with the periphery of the wheel and to depress the tape into the groove, and means for rotating the roller and the wheel with the peripheral speed of the roller equal to the peripheral speed of the bottom of the groove.

6. The mechanism of claim 5 in which the periphery of the pull-off roller is knurled.

7. The mechanism of claim 5 in which the groove in the periphery of the wheel is V-shaped in cross section.

8. The mechanism of claim 7 in which the periphery of the pull-off roller is knurled.
